DESIGN FOR A SACHET

Nancy Goodstein, New York, N. Y.

Application December 4, 1940, Serial No. 97,052

Term of patent 3½ years

To all whom it may concern:

Be it known that I, Nancy Goodstein, a citizen of the United States of America and resident of Borough of Manhattan, city, county, and State of New York, have invented a new, original, and ornamental Design for a Sachet, of which the following is a specification, reference being had to the accompanying drawing, forming part thereof.

In the accompanying drawing the figure is a perspective view of a sachet showing my new design.

I claim:
The ornamental design for a sachet, as shown.

NANCY GOODSTEIN.
